US0D1106135S

(12) **United States Design Patent** (10) **Patent No.:** **US D1,106,135 S**
(45) **Date of Patent:** **** Dec. 16, 2025**

(54) **ADAPTER FOR A MOBILE DEVICE**

(71) Applicant: **Peak Design**, San Francisco, CA (US)

(72) Inventors: **Kiran Malladi**, San Francisco, CA (US); **Matthew Thomas James**, San Francisco, CA (US); **Arthur Viger**, San Francisco, CA (US); **Olivia Eaton**, San Francisco, CA (US); **Jaimee Erickson**, San Francisco, CA (US); **Colin Maginnis**, San Francisco, CA (US)

(73) Assignee: **Peak Design**, San Francisco, CA (US)

(**) Term: **15 Years**

(21) Appl. No.: **29/778,080**

(22) Filed: **Apr. 9, 2021**

Related U.S. Application Data

(63) Continuation of application No. 17/067,612, filed on Oct. 9, 2020, now Pat. No. 11,548,451, which is a continuation-in-part of application No. 16/945,687, filed on Jul. 31, 2020, now Pat. No. 11,585,485.

(57) **CLAIM**

The ornamental design for an adapter for a mobile device, as shown and described.

DESCRIPTION

FIG. 1 is a perspective front view of an adapter for a mobile device showing our new design.

FIG. 2 is a perspective back view of the adapter for a mobile device.

FIG. 3 is an elevational front view of the adapter for a mobile device.

FIG. 4 is an elevational back view of the adapter for a mobile device.

FIG. 5 is a top plan view of the adapter for a mobile device; and,

FIG. 6 is a side elevational view of the adapter for a mobile device.

The broken lines in the drawing figures form no part of the claimed design; they illustrate environmental subject matter and portions of the adapter for a mobile device that form no part of the claimed design.

1 Claim, 5 Drawing Sheets
